TRANSMITTER

Filed April 14, 1921

Friedrich H. N. Wohlers INVENTOR.

BY

Rosenbaum Stockbridge & Bass ATTORNEYS.

UNITED STATES PATENT OFFICE.

FRIEDRICH H. N. WOHLERS, OF JAMAICA, NEW YORK, ASSIGNOR TO DICTOGRAPH PRODUCTS CORPORATION, A CORPORATION OF VIRGINIA.

TRANSMITTER.

Application filed April 14, 1921. Serial No. 461,283.

To all whom it may concern:

Be it known that I, FRIEDRICH H. N. WOHLERS, a citizen of the United States, residing at Jamaica, in the county of Queens 5 and State of New York, have invented certain new and useful Improvements in Transmitters, of which the following is a full, clear, and exact description.

In carbon ball transmitters utilizing a 10 plurality of very small carbon balls in pockets of a conducting element and engaged by a diaphragm, such as disclosed for example in U. S. Patent No. 844,635, it has been found that if the transmitter is subjected to 15 jars or shocks such as are occasioned by dropping of the transmitter, the diaphragm often springs or flexes away from the conducting element or pockets sufficiently to allow the small balls to escape entirely from 20 the pockets of the elements or to become wedged between the diaphragm and the portion of the conducting element surrounding the pockets, with the result that the diaphragm either cannot vibrate at all or the 25 absence of the balls from the pockets prevents or limits the passage of current between the diaphragm and the conducting element.

The object of my invention is to provide 30 a carbon ball transmitter in which it is impossible for the balls to get out of place or lost, to generally improve and simplify the construction of transmitters of this type, eliminate difficult and expensive machine 35 work in their manufacture, and improve the attachment of the face cap to the casing. Other objects and advantages will be apparent from the following description and the novel features of my invention will be 40 particularly pointed out in claims.

In carrying my invention into practice I support an abutment adjacent the face of the diaphragm and opposite the conducting element, but spaced therefrom sufficiently 45 to permit of the normal vibration of the diaphragm and acting to limit excessive movement of the diaphragm such as would release the balls from the cavities of the conducting element. The same abutment is 50 also preferably utilized as the support for the face cap of the instrument. The invention also comprises certain details and arrangements which will be hereinafter more particularly described in connection with 55 the illustrated embodiment of my invention.

In the drawings:

Fig. 1 is a front elevation of a transmitter constructed in accordance with my invention;

Fig. 2 is a section of the same taken substantially along the line 2—2 of Fig. 1;

Fig. 3 is a plan of a detail of the transmitter, and

Fig. 4 is a plan of the cup carrying the 65 conducting elements.

A suitable handle 1 is provided at one end with connections 2 for a twin cable 3 entering the same and by means of which the instrument is connected to any suitable external circuit. The opposite end of the 70 handle terminates in a casing 4 having an open face in which is disposed the transmitter mechanism proper. A cup 5 is removably disposed within the bottom of the casing 4 and carries a pair of carbon blocks 75 6 which are secured thereto by screws 7. Insulating pads 8 are interposed between the carbon blocks 6 and the bottom of the cup for insulating the blocks therefrom and suitable insulation 9 is interposed between 80 the two blocks. A contact plate 10 is interposed between each block and its insulating pad and has an enlarged aperture 11 for the passage of the securing screw 7. An 85 insulating sleeve 12 surrounds each screw 7 so as to insulate it from the contact plate 10 and carbon block, the head of the screw being countersunk below the face of the carbon block. Each block is provided with a plurality of cavities or depressions 13 in its outer face, in which are disposed a plurality 90 of small carbon balls 14. A diaphragm 15 of conducting material is clamped across the upper face of the cup at the periphery thereof by means of a suitable disk like ele- 95

ment or member 16 which is threaded into the interior of the open end of casing 4, suitable gaskets 17 being interposed between the diaphragm and both the element 16 and the cup 5 so as to insulate the diaphragm 100 from the casing. The depth of the cup 5 is such as to cause the diaphragm to be disposed in a slightly spaced relation to the outer faces of the carbon blocks and retain the balls 14 within the cavities and at the same time be free to vibrate slightly without contacting with the carbon blocks. The disk-like element 16 has an opening 18 in its central portion which is bridged by arms 19 carrying at their junction a boss 20. The 110

boss 20 extends towards, but is slightly spaced from the diaphragm 15 upon the face of the latter opposite the carbon blocks so as to limit the movement of the diaphragm 5 away from the carbon blocks to that extent necessary for its normal vibration and prevent movement to an extent sufficient to release the balls from the cavities. The boss is provided with a threaded aperture 21 10 which receives a threaded stem 22 of a cap plate 23 which closes the outer face of the casing 4. The cap plate is provided with suitable openings 24 for permitting entrance of the sound waves to the casing in order 15 to actuate the diaphragm and through it vary the resistance of the circuit. The carbon blocks are connected through their contact plates 10 and wires 11 with the connections 2 in the opposite end of the handle. 20 The external circuit is connected to the instrument by cable 3, the current passing through one of the wires 11 to one of the contact plates 10, the carbon block 6 carried thereby, the carbon balls in the pockets of 25 that block, a diaphragm in contact therewith, through the diaphragm, then through the carbon balls of the other carbon block which are in contact therewith, the other carbon block, its contact plate 10 and the 30 corresponding wire 11 back to the cable 3. As the sound waves enter the apertures 24 of the casing they impinge upon the diaphragm and set the latter in vibration. The diaphragm in vibrating displaces the carbon balls in their pockets and by this displacement varies the resistance through the 35 same and causes a fluctuation in the current passing through the circuit described. This variation in the current in the circuit is utilized 40 at another point in the circuit for the reproduction of the sound waves in a manner well known in the art. If the transmitter should be accidentally dropped or subjected to severe shocks, the diaphragm 45 will be prevented from moving away from the carbon blocks sufficiently to allow the balls to escape from the pockets, owing to the contact of the diaphragm with the abutment boss 20 upon an excessive flexure of 50 the diaphragm. The boss also acts as a support for the stem projecting from the cap which eliminates the necessity of threading the cap to fit the casing and enables the 55 cap to be stamped from sheet metal and the stem which can be inexpensively produced in automatic machines can be attached thereto by riveting.

The cap can be produced in various finishes or designs to match furniture or other 60 fittings and attached to a standard transmitter so as to eliminate the necessity of producing the entire transmitter in various particular finishes thus considerably lessening the cost and stock which should be carried.

It will be obvious that various details and changes in the construction herein described and illustrated may be made by those skilled in the art within the principle and scope of the invention.

70

I claim:

1. In a telephone transmitter, a block of conducting material having cavities in a face thereof, a diaphragm in juxtaposition to but slightly spaced from said block and 75 cavities, a plurality of small balls confined in each of said cavities by the diaphragm, and an abutment adjacent to but slightly spaced from the face of the diaphragm opposite to the block whereby movement of the 80 diaphragm away from the block sufficiently to release the balls from the cavities will be prevented without restricting normal vibratory movement of the diaphragm.

2. In a telephone transmitter, a conduct- 85 ing element having a cavity in a face thereof, a diaphragm supported in juxtaposition to but slightly spaced from the said face of the element, a plurality of small balls confined within the cavity by the diaphragm, 90 and means permitting normal vibratory movement of the diaphragm but preventing an amplitude of movement of the same sufficient to release the balls from the cavity.

3. In a telephone transmitter, a casing, a 95 conducting element having a cavity in a face thereof carried within the casing, a diaphragm supported in juxtaposition to but slightly spaced from the said face of the element, a plurality of small balls confined 100 within the cavity by the diaphragm, and a member carried by the casing for clamping the diaphragm and element in position in the casing and having a portion in juxtaposition to but slightly spaced from the central portion of the diaphragm opposite the conducting element for preventing an amplitude of movement of the diaphragm sufficient to release the balls from the cavity.

4. In a telephone transmitter, a casing, a 110 conducting element having a cavity in a face thereof carried within the casing, a diaphragm supported in juxtaposition to but slightly spaced from the said face of the element, a plurality of small balls confined 115 within the cavity by the diaphragm, a member carried by the casing for clamping the diaphragm and element in position in the casing and having a portion in juxtaposition to but slightly spaced from the central portion of the diaphragm opposite the conducting element for preventing an amplitude of movement of the diaphragm sufficient to release the balls from the cavity, and a perforated cap for closing the casing 120 carried by the member.

5. In a telephone transmitter, a casing, a 125 conducting element having a cavity in a face thereof carried within the casing, a diaphragm supported in juxtaposition to 130

- but slightly spaced from the said face of the element, a plurality of small balls confined within the cavity by the diaphragm, a member carried by the casing for clamping the diaphragm and element in position in the casing and having a portion in juxtaposition to but slightly spaced from the central portion of the diaphragm opposite the conducting element for preventing an amplitude of movement of the diaphragm sufficient to release the balls from the cavity and a perforated cap for closing the casing detachably carried by the member, said cap and member having apertures permitting passage of sound waves to the diaphragm from the exterior of the casing. 65
6. In a telephone transmitter, a casing having an open face, a cup removably disposed in the bottom of the casing and opening toward the open face of the casing, a conducting element carried within the cup and having a cavity in its outer face, a diaphragm closing the open face of the cup and passing in juxtaposition to but spaced slightly from the said outer face of the conducting element, a plurality of small balls confined within the cavity by the diaphragm, and a member adjustably engaging with the casing to clamp the diaphragm against the edge of the cup and both against the rear wall of the casing. 70
7. In a telephone transmitter, a casing having an open face, a cup removably disposed in the bottom of the casing and opening toward the open face of the casing, a conducting element carried within the cup and having a cavity in its outer face, a diaphragm closing the open face of the cup and passing in juxtaposition to but spaced slightly from the said outer face of the conducting element, a plurality of small balls confined within the cavity by the diaphragm, and a member adjustably engaging with the casing to clamp the diaphragm against the edge of the cup and both against the rear wall of the casing. 75
8. In a telephone transmitter, a casing having an open face, a cup removably disposed in the bottom of the casing and opening toward the open face of the casing, a conducting element carried within the cup and having a cavity in its outer face, a diaphragm closing the open face of the cup and passing in juxtaposition to but spaced slightly from the said outer face of the conducting element, a plurality of small balls confined within the cavity by the diaphragm, and a member adjustably engaging with the casing to clamp the diaphragm against the edge of the cup and both against the rear wall of the casing, said member having an opening for the passage of sound waves to the diaphragm and also having a portion in juxtaposition to but slightly spaced from the central portion of the diaphragm for preventing movement of the diaphragm away from the conducting element to an extent sufficient to release the balls from the cavity, and a perforated cap detachably carried by the member for closing the open face of the casing. 80
9. In a telephone transmitter, a casing having an open face, a cup removably disposed in the bottom of the casing and opening toward the open face of the casing, a conducting element carried within the cup and having a cavity in its outer face, a diaphragm closing the open face of the cup and passing in juxtaposition to but spaced slightly from the said outer face of the conducting element, a plurality of small balls confined within the cavity by the diaphragm, and a member adjustably engaging with the casing to clamp the diaphragm against the edge of the cup and both against the rear wall of the casing, said member having an opening for the passage of sound waves to the diaphragm and also having a portion in juxtaposition to but slightly spaced from the central portion of the diaphragm for preventing movement of the diaphragm away from the conducting element to an extent sufficient to release the balls from the cavity, and a perforated cap detachably carried by the member for closing the open face of the casing. 85
10. In a telephone transmitter, a casing having an open face, a cup removably disposed in the bottom of the casing and opening toward the open face of the casing, a conducting element carried within the cup and having a cavity in its outer face, a diaphragm closing the open face of the cup and passing in juxtaposition to but spaced slightly from the said outer face of the conducting element, a plurality of small balls confined within the cavity by the diaphragm, and a member adjustably engaging with the casing to clamp the diaphragm against the edge of the cup and both against the rear wall of the casing, said member having an opening for the passage of sound waves to the diaphragm and also having a portion in juxtaposition to but slightly spaced from the central portion of the diaphragm for preventing movement of the diaphragm away from the conducting element to an extent sufficient to release the balls from the cavity, and a cap for closing the casing and having a threaded stem projecting centrally therefrom, said boss having a threaded aperture for receiving said threaded stem thereby and detachably securing the cap to the casing, said cap and member having open portions permitting the passage of sound waves from the exterior of the casing to the diaphragm. 90
- In witness whereof I hereunto subscribe my signature.
